DESIGN FOR A COMBINED LIGHTER AND CIGARETTE AND CIGAR CONTAINER

David W. Dunberg, New York, N. Y.

Application June 29, 1940, Serial No. 93,364

Term of patent 7 years

To all whom it may concern:

Be it known that I, David W. Dunberg, a citizen of the United States of America, residing in the city of New York, county of New York, and State of New York, have invented a new, original, and ornamental Design for a Combined Lighter and Cigarette and Cigar Container, of which the following is a specification, reference being had to the accompanying drawing, forming part thereof.

The figure on the drawing is a front perspective view of a combined lighter and cigarette and cigar container showing my new design.

The rear view is the same as the front view except for the slot opening at the lower portion.

I claim:

The ornamental design for a combined lighter and cigarette and cigar container, as shown and described.

DAVID W. DUNBERG.
